(57) **CLAIM**

The ornamental design for safety child seat fixed on a base, as shown and described.

DESCRIPTION

1. Safety child seat fixed on base

1.1 is a rear view.

1.2 is a bottom view.

1.3 is a front view.

1.4 is a right side view.

1.5 is a perspective view.

1.6 is a left side view.

1.7 is a top view.

In the drawings, the broken lines represent portions of the child seat that form no part of the claimed design.
